ELECTRICAL STIRRUP CONNECTOR

Leonard S. Greer, Erie, Pa., assignor to Penn-Union Electric Corporation, Erie, Pa., a corporation of Pennsylvania

Filed Oct. 1, 1959, Ser. No. 843,873
3 Claims. (Cl. 174—71)

The present invention relates generally to a novel electrical connector and more particularly to a novel stirrup type connector.

An important object of the present invention is to provide a novel stirrup type device utilizing a compression connector and a wire bail or stirrup, which device is constructed so that the wire bail or loop may be readily assembled with the compression connector and adjusted to any desired position relative thereto whereupon the connector may be compressed on a power line so that the bail or loop will be secured in the desired adjusted position.

A more specific object of the present invention is to provide a novel stirrup type connector or device of the above described type wherein the compression means is provided with a bore or passageway for accommodating a portion of the wire bail or loop, which portion of the wire bail is constructed for locking the bail in the desired adjusted position relative to the compression means when the device is fully applied to a power line or the like.

An even more specific object of the present invention is to provide a novel stirrup type connector or device of the above described type which is constructed so as to control movement or adjustment of the wire bail both axially and rotatably relative to the compression unit for facilitating proper assembly of the device with a power line or the like.

Another object of the present invention is to provide a novel stirrup type device or connector which is constructed so that a wire bail or stirrup may be securely fastened to a compression unit during the same compression operation by which the unit is applied to a power line.

Other objects and advantages of the present invention will become apparent from the following description and the accompanying drawings wherein:

FIG. 1 is a simplified view showing a power distribution system utilizing a stirrup connector of the type contemplated by the present invention;

FIG. 2 is an enlarged fragmentary side elevational view showing a stirrup type connector or device incorporating features of the present invention fully applied to a power line and also connected with a plurality of tap wires;

FIG. 3 is a fragmentary sectional view taken along line 3—3 in FIG. 2;

FIG. 4 is a sectional view similar to FIG. 3 but showing the device prior to the crimping or compression operation by which the compression unit is secured both to the main power line and the bail or wire loop of the device;

FIG. 5 is a fragmentary side elevational view similar to FIG. 2 but showing a slightly modified form of the present invention;

FIG. 6 is an enlarged fragmentary perspective view showing a portion of the wire bail of the device shown in FIG. 5;

FIG. 7 is a fragmentary side elevational view showing another slightly modified form of the present invention;

FIG. 8 is an enlarged fragmentary vertical partial sectional view of the device shown in FIG. 7; and

FIG. 9 is a fragmentary side elevational view showing another modified form of the present invention.

2

Referring now more specifically to the drawings wherein like parts are designated by the same numerals throughout the various figures, a device 10 incorporating features of the present invention is shown in FIGS. 1—4.

5 As will be understood, stirrup type devices or connectors are especially suitable for application to an energized line or conductor so as to permit tapping thereof without arcing damage. Thus FIG. 1 shows a power distribution system which includes an energized line 12 to which one or more tap wires 14 may be connected through the device 10.

As shown best in FIGS. 2, 3, and 4, the device 10 includes a unit 16 formed from a suitable material so that it is adapted to be compressed onto the power line 12 for connection thereto. For example, in the event the power line 12 is an aluminum conductor, the compression unit 16 is preferably formed from aluminum or an alloy thereof. The device 10 also includes a wire loop or bail 18 formed from a suitable electricity conducting material such, for example, as copper.

As shown in FIG. 4, the compression unit 16 is initially formed so that it comprises an upper marginal flange or hook portion 20 which has an arcuate transverse cross section and which is adapted to be applied over the conductor 12 in the manner shown for retaining the device 10 in association with the conductor prior to the crimping or compressing operation. The upper arcuate flange section merges with a side portion 22 of the compression unit body from which extends an intermediate web or flange portion 24, and a lower marginal arcuate flange portion 26. The intermediate portion 24 terminates in a depending relatively short flange 28 which complements the remainder of the intermediate section 24 and the lower arcuate marginal flange 26 in providing the unit with a bore or passageway 30 adapted to receive portions of the wire bail or stirrup 18.

The bail or stirrup 18 is formed from a wire having a generally round cross section with a diameter preferably less than the transverse dimensions or the diameter 40 of the bore 30 in the compression unit 16. In this embodiment the bail is provided with a central horizontal portion 32 merging at its opposite ends with upstanding leg portions 34 and 36 which in turn merge with inwardly directed end portions 38 and 40.

45 It is to be noted that in accordance with an important feature of the present invention, terminal end sections 42 and 44 of the bail portions 38 and 40 are flattened to a non-circular configuration. Thus when the unit 16 is crimped or compressed as shown in FIG. 3, the non-circular sections 42 and 44 positively interlock with the collapsed flanges 26 and 28 to prevent the bail from rotating or twisting relative to the unit 16. It will further be noted that, in this embodiment, the sections 42 and 44 are flattened and radially expanded so that their major transverse dimensions are similar to the transverse dimensions or diameter of the bore 30 so that the sections 42 and 44 have a friction fit within the bore. This friction fit between the sections 42 and 44 and the surface of the bore 30 serves to resist slipping of the bail axially of

50 the bore from the desired centered relationship with the unit 16 as shown in FIG. 2. The friction fit may also serve to retain the bail in any desired adjusted position to which it may be rotated about the common axis of the portions 38 and 40 and the bore 30 prior to the completion of the crimping or compressing operation. In certain instances a more positive preliminary interlock may be obtained by creasing or pinching the side portion 22 in the vicinity of the bore 30 so as to collapse the bore slightly.

70 When installing a stirrup type connector or device 10, the unit 16 is hooked around the line 12 as shown in

FIG. 4 and then with the bail or stirrup member frictionally held in the desired adjusted position relative to the unit 16, a workman crimps or compresses the unit 16 to the condition shown in FIG. 3 with the aid of a suitable tool, not shown. Then one or more tap wires may be applied to the various portions of the bail or stirrup member 18 as shown best in FIG. 2. Suitable connectors 46 are used for securing the tap wires 14 to the bail member and, if desired, the connectors 46 may have essentially the same construction as the unit 16.

FIGS. 5 and 6 show a modified embodiment of the present invention which is similar to the structure described above as indicated by the application of identical reference numerals with the suffix *a* added to corresponding elements. This embodiment differs in that in addition to the flattened end sections 42*a* and 44*a*, the bail portions 33*a* and 40*a* are provided with enlargements 48 and 50. As indicated, these enlargements may be formed by further flattening and radially extending the wire adjacent the flattened end sections so that the enlargements are adapted to engage opposite ends of the body of the unit 16 for positively preventing relative movement between the bail and the unit 16*a* axially of the bore 30*a*. In addition the leg portions 34*a* and 36*a* of the bail are flexed so that the enlargements 48 and 50 are aggressively urged against the opposite ends of the compression unit for frictionally retaining the bail in any position to which it may be adjusted or rotated relative to the compression 16 about the axis of the bore 30*a*.

FIGS. 7 and 8 show a device 18*b* embodying a further slightly modified form of the present invention. This embodiment closely resembles the structure shown in FIGS. 5 and 6 except that the diameter of the wire bail is relatively small as compared with the diameter of the bore 30*b* so that the major dimension of the enlargements 48*b* and 50*b* may not be sufficient to enable the enlargements to function by themselves to locate and retain the bail in the desired relationship with respect to the compression unit. Thus washer like elements 52 and 54 are applied over the end sections 42*b* and 44*b*, which washer elements have internal diameters less than the major dimension of the enlargements 48*b* and 50*b* and external diameters substantially greater than the diameter of the bore 30*b* so that the washers in combination with the enlargements function to locate the bail in the desired manner with respect to the compression unit.

FIG. 9 shows a device 18*c* which is similar to the structures described above as indicated by the application of identical reference numerals with the suffix *c* added to corresponding elements. In this embodiment the portions 33*c* and 40*c* of the wire stirrup or bail are turned outwardly away from each other rather than inwardly toward each other and two identical compression units 16*c* are provided respectively for receiving the end sections 42*c* and 44*c* of the bail. The flattened sections 42*c* and 44*c* are formed so that they extend entirely through their associated compression units, and after preliminary assembly of the compression units and the sections 42*c* and 44*c* has been accomplished, outer terminal ends of the flattened sections are further pinched and radially expanded to provide additional enlargements 56 and 58 for retaining the compression units in associa-

tion with the bail member prior to the crimping or compressing operation. It will be appreciated that with this structure the length of the intermediate bail section 32*c* may be extended for accommodating a plurality of tap wire connectors.

While the preferred embodiments of the present invention have been shown and described herein, it is obvious that many structural details may be changed without departing from the spirit and scope of the appended 10 claims.

The invention is claimed as follows:

1. A stirrup-type connector device for making tap connections to an electric power line comprising: a wire bail of electrically conductive material having a central portion terminating at its ends in upstanding leg portions, each of said leg portions merging into an end means, each of said end means including a preliminarily formed, flattened section having a minor transverse dimension and a major transverse dimension exceeding said minor dimension, each of said end means further including a preliminarily formed enlargement situated adjacent at least the inner end of said flattened section, said enlargement having a major dimension exceeding the major transverse dimension of said flattened section; means for coupling 20 said bail to said power line including a body of deformable, electrically conductive material having a hook portion adapted to receive and be crimped snugly about a section of said power line and having arcuate flanges defining a bore with its axis disposed parallel to said power line, said bore initially having a transverse dimension at least no greater than the major transverse dimension of said flattened sections for receiving at least one of said flattened sections in a press fit, crimping of said flanges non-rotatably securing said bail to said coupling means, 30 a said enlargement confronting said body to block axial movement of said bail relative thereto; and means for affixing a tap wire to said bail away from said body.

2. A stirrup-type connector according to claim 1 wherein in the terminal portions of said end means confront each other to define a discontinuity in said bail and wherein the enlargements at the inner ends of said flattened sections are spaced apart by a distance less than the axial extent of said body whereby said last mentioned enlargements are biased into frictional engagement with the ends 45 of said body.

3. A stirrup-type connector according to claim 1 and further comprising a washer element disposed on said flattened section between the enlargement at the inner end thereof and said body.
